PRONG FASTENER FOR BINDERS, FOLDERS,
AND THE LIKE

Max Vogel, Bridgeport, Conn.

Application September 8, 1937, Serial No. 162,835

1 Claim. (Cl. 24—153)

The present invention relates to a prong fastener for binders, folders, and the like, particularly of the type consisting of a bendable metal strip having an intermediate portion which engages the under side of papers or the like to be bound together, and prongs at each end which are inserted through openings in the papers and then inserted through openings in a binder member, and upon which member the extremities of the prong portions are bent into flat relation, being usually locked in this relation by means of a slide member. These heretofore known fasteners have the disadvantage that when the prongs are bent, permanent kinks are produced therein which cannot later be straightened out, so that it becomes difficult to remove or insert papers without tearing the holes therein. As a result the prongs do not stay or lie straight, are apt to fracture, and the fastener becomes loose if any appreciable strain is applied thereto. Also the prongs have sharp and rough edges which are apt to cut the fingers of persons using the fastener.

An object of the present invention is to provide a fastener which eliminates these disadvantages, and to this end it is proposed to provide prong sections which are corrugated, the corrugations forming a series of bending points which can be repeatedly bent without destroying the original form of the prong, thereby facilitating the use of the fastener repeatedly for different thicknesses of papers. These corrugations also have the advantage that they provide predetermined permanent bending points about which the prongs may be bent at sharp right angles, without however excessively bending the material so that it would be apt to fracture. Another object is to provide a fastener in which the corrugations of the prong portions eliminate sharp dangerous edges, and further to increase the surface contact of the prongs with the holes in the papers, so that tearing or cutting of the holes is prevented.

A further object is to provide a fastener having corrugations in the prong portions and a non-corrugated tip portion, this tip portion adapted to facilitate the engagement of the fastener in the holes of the papers, and also indicating the extent to which the papers may be placed upon the fastener, the corrugation adjacent the tip portion being the limit which indicates the maximum capacity of the fastener at which point the prong may be bent. A further object is to provide a fastener in which the prong portions will stand straight and relatively

rigid when straightened out, so that papers may be readily removed or easily inserted at any place within the folder.

A further object is to provide a fastener in which the prongs will resist strain to a much greater extent than the smooth prongs heretofore in use, and which will provide a positive locking action when bent in relation with the binder member. Another object is to provide a fastener in which the corrugations of the prongs are adapted to cooperate with locking slide members so that the latter will remain in any position to which they are adjusted.

With the above and other objects in view, embodiments of the invention are shown in the accompanying drawing, and these embodiments will be hereinafter more fully described with reference thereto, and the invention will be finally pointed out in the claim.

In the drawing:

Fig. 1 is a side elevation of a fastener according to the illustrated exemplary embodiment of the invention.

Fig. 2 is a plan view thereof.

Fig. 3 is a fragmentary plan view of one end of a modified form of fastener according to the invention.

Fig. 4 is a fragmentary plan view of one end portion of another form of fastener, according to the invention.

Fig. 5 is a plan view showing the fastener engaged in a folder of papers and in interlocking relation with the binder strip.

Fig. 6 is a sectional view taken through the lines 6—6 of Fig. 5.

Fig. 7 is a fragmentary plan view showing the fastener in relation to a modified form of binder member having locking slide members.

Fig. 8 is a sectional view taken along the line 8—8 of Fig. 7.

Similar reference characters indicate corresponding parts throughout the several figures of the drawing.

Referring to the drawing and more particularly to Figs. 1 and 2 thereof, the fastener shown therein consists of a flexible bendable metal strip of uniform width throughout, so that it may be economically formed of ordinary strip material, and consisting of an intermediate portion 10 and prong portions at each end thereof, each comprising a corrugated section 11 having series of corrugations 12 at each edge extending above and below the plane of the intermediate portion of the strip between the corrugations, and a tip portion 13 preferably pointed at its end.

The intermediate portion 10 is provided with a plurality of longitudinally extending ribs 14 pressed therein to render it relatively stiff and the tip portions 13 are similarly provided with longitudinally extending stiffening ribs 15. It will be understood however that these may be dispensed with either in the intermediate portion, or in the tips, or both. It will be noted that the corrugations 12 at each edge are transversely aligned so that the prong may be bent at a true right angle at any desired point. As shown in Fig. 1 the edge has a serpentine form and therefore presents a much greater surface area than would a straight edge, and this has the advantage that it will not cut the fingers and will provide relatively large surface contact areas for engagement with the holes in the papers to be bound.

In Fig. 3 I have shown corrugations 16 in the prong portions 11 disposed intermediate the longitudinal edges and which form bending lines substantially similar to the corrugations shown in Figs. 1 and 2.

The uncorrugated portions of the prongs as shown in Figs. 2 and 3, prevent weakening of the material when it is bent in relation to the corrugations. The corrugations give flexibility to the material without sacrificing stiffness, and therefore thicker or harder material can be used, if desired.

In Fig. 4 I have shown prong portion 11 provided with corrugations 17 extending the full width of the portion 11, and I have also shown the intermediate portion 10^a of greater width than the prong portion. It will be understood that the intermediate portion may be of the same width as the prong portion, as shown in Figs. 1 to 3, and also that in the embodiments shown in Figs. 1 to 3 the intermediate portion may be of greater width, as shown in Fig. 4.

The papers 18 to be bound are each provided with registering holes 19-19 spaced the same distance as the length of the intermediate portion 10. The prongs of the fastener are bent at right angles at the ends of the intermediate portion 10 and are inserted through the holes 19-19 being then inserted through holes 20-20 in a metal binder strip 21. The prongs are then bent either inwardly or outwardly into parallel relation with the upper surface of the retaining member 21, the bends being coincident with the

corrugations. These bends will lock with relation to the holes 20-20 and when it is desired to remove or insert papers the prongs may be bent into upright relation without producing any noticeable change in the structure of the prong portion, such as the kind usually produced in the plain surfaced prong portions heretofore in use.

In Figs. 7 and 8 I have shown a modified form of binder strip member 22 having marginal flange portions 23-23 bent inwardly at each edge to provide grooves in which the outwardly bent flanges 24-24 of a locking slide member 25 are engaged, this sliding member being of channel form so that the bent end of the prong will be received therein. The surface of the slide member is preferably corrugated, as at 26, for the purpose of facilitating the sliding thereof, and these corrugations may if desired conform to the corrugations of the prongs. Upon the inner end of the slide member there is provided a downwardly bent locking lip 27 which will lockingly engage in the corrugations of the prong portion thereby preventing the possibility of any displacement of accidental movement of the slide member.

I have illustrated and described preferred and satisfactory embodiments of the invention, but it will be obvious that changes may be made therein, within the spirit and scope thereof, as defined in the appended claim.

Having thus described my invention, what I claim and desire to secure by Letters Patent is:

In a fastener of the character described, a strip of material having an intermediate portion and prong portions at each end adapted to be bent at an angle to the ends of said intermediate portion and to be angularly bent intermediate their ends, said prong portions each having an intermediate longitudinal uncorrugated portion and at each longitudinal edge a plurality of successive arranged alternately upwardly and downwardly projecting transverse corrugations extending for a substantial distance along said prong portion and constituting a plurality of preformed contiguous arranged bending portions, the descending side walls of the alternate upwardly projecting corrugations being the ascending side walls of the alternate downwardly projecting corrugations.

MAX VOGEL.
